UNITED STATES PATENT OFFICE

JAN STRENG, OF NEW YORK, N. Y., ASSIGNOR TO KOLSTER RADIO, INC., OF NEW YORK,
N. Y., A CORPORATION OF NEW JERSEY

DESIGN FOR A RADIOCABINET

Application filed September 25, 1931. Serial No. 41,219. Term of patent 3½ years.

To all whom it may concern:

Be it known that I, JAN STRENG, a citizen of the United States, and a resident of New York, in the county of New York and State of New York, have invented a new, original, and ornamental Design for Radiocabinets, of which the following is a specification, reference being had to the accompanying drawing, forming a part thereof. The sides of the cabinet have a recessed plain panel framed by the extension of the top, by the front corner mouldings and by back corner mouldings

as well as by a bottom moulding. The side view of these mouldings conforms to the corner mouldings as seen from the plan view.

The figure shows a front perspective view of the radiocabinet.

I claim:

The ornamental design for a radiocabinet, as shown.

In witness whereof, I hereunto subscribe my name this 11th day of September, 1931.

JAN STRENG.
